METHOD AND APPARATUS FOR COATING
SHEET MATERIALSHorace A. Sheesley, Portland, Maine, assignor
to Tufide Products Corporation, Portland,
Maine, a corporation of Maine

Application November 2, 1936, Serial No. 108,789

5 Claims.

(Cl. 91—68)

This invention relates to an improved method and apparatus for coating sheet materials, and more particularly to a method and apparatus for applying a uniform coating compound to sheet materials such as paper, paperboard, textiles, and the like, and also to an improved waterproof and greaseproof paper and paperboard which can be economically and expeditiously manufactured by my improved method and apparatus.

Paper and paperboard material have heretofore been treated with a coating of wax, paraffin or asphalt to make the same resistant to moisture. Wax and paraffin is expensive material, and to a certain extent difficult to apply due to the heating and cooling treatment required. Asphalt is also difficult and expensive to apply, requiring expensive machinery and equipment. A further serious drawback of wax and paraffin and asphalt coatings is that they are affected by heat and temperature changes. Wax melts at approximately 130° F. and at this temperature will flow off and lose its waterproofing qualities. Both wax, paraffin and asphalt soften to much lower temperature, rendering the surface sticky and tacky and generally undesirable for commercial purposes.

A coating resistant to the passage of grease and oil therethrough has long been sought for. Wax, paraffin and asphalt coated papers are only partially resistant to the passage of grease and oil therethrough and are not satisfactory, since they soften under moderately warm atmospheres rendering the same greasy, sticky and porous.

It is an object of my invention to provide an improved paper and paperboard material suitably treated so as to make the same waterproof, greaseproof and oilproof.

Another object of my invention is to provide a waterproof and greaseproof paper and paperboard which can be manufactured at low cost, quickly and expeditiously, which has greater strength and flexibility than treated papers heretofore provided, which will not crack or deteriorate by flexure or rough handling, which is odorless and does not deleteriously effect foods and other products packed therein, which is furthermore not affected by heat or temperature changes and which is a fire and combustion retardant.

Another object of this invention is to provide an improved coating composition which is substantially waterproof and greaseproof.

Still another object of this invention is to provide an improved method and improved ap-

paratus for coating paper, paperboard, paper stock of all kinds and other sheet materials which can be carried out expeditiously and economically and by which a high quality coated material can be produced.

Another object of this invention is to provide an improved apparatus for manufacturing coated papers, paperboard, paper stock and other sheet materials which is low in cost as compared with apparatus heretofore used for such purposes, which can be operated with a minimum of attention and largely by unskilled labor, which is durable and lasting in construction, and which permits manufacture of coated paper and paperboard and other coated sheet materials so as to produce a highly satisfactory and desirable product efficiently, expeditiously and at low cost.

Other objects of this invention will become apparent as the disclosure proceeds.

In accordance with this invention, the paper, paperboard or other sheet material to be coated is supplied in suitable rolls or in sheets. My improved coating composition is applied to the rolls or sheets by spray mechanism which applies a homogeneous and uniform coating on the sheet material as it moves continuously under the spray mechanism. Immediately after the application of the coating, the surface is subjected to a pressing and spreading action which forces still further the coating composition into the outer fibres of the sheet and spreads the coating in a smooth, even and homogeneous layer thereover. The coated web is thereafter run through a suitable drying chamber which operates to hasten the escape of the evaporable components of the coating solution and also hastens the solidification or hardening of the coating material upon the moving web.

It will be noted that the coating is applied while the stock is in dry or substantially dry condition and thus the web can be easily and efficiently handled. The coating composition comprises a latex solution which may be combined with a fat-free animal glue, such as fish glue, animal glue or gelatin. The ordinary vegetable glues such as those made from starches now available commercially have not proven satisfactory. A suitable preserving agent, such as formaldehyde, is added to the mixture and a congealing agent, such as an alcohol, is applied to the mixture which serves to congeal the same when spread over the sheet or web material.

Various other features and advantages of the invention will be apparent from the following

particular description and from an inspection of the accompanying drawings.

Although the novel features which are believed to be characteristic of this invention will be particularly pointed out in the claims appended hereto, the invention itself, as to its objects and advantages, and the manner in which it may be carried out, may be better understood by referring to the following description taken in connection with the accompanying drawings forming a part thereof, in which:

Fig. 1 is a top plan view of my improved apparatus for making the waterproofed paper and paperboard by the method herein described, certain parts being broken away to expose the interior;

Fig. 2 is a side elevational view of the complete apparatus, the apparatus-enclosing housing being broken away to expose the same to view;

Fig. 3 is an enlarged front elevational view of the apparatus showing particularly the coating applicator operating in conjunction with the spreader knife to apply a uniform layer of the coating material to the paper surface;

Fig. 4 is an enlarged fragmentary diagrammatic view showing the arrangement of the spreader knife, the coating applicator, and if desired an applicator by which a suitable hardening accelerator may be separately applied;

Fig. 5 is a vertical longitudinal cross-sectional view of a coating apparatus designed to apply coating to both surfaces of the web; and

Fig. 6 is a magnified cross-sectional view showing a section of paper or paperboard having my improved waterproof greaseproof coating applied to both surfaces thereof.

Similar reference characters refer to similar parts throughout the several views of the drawings and specification.

I have found that a mixture of rubber latex and fat-free glue provides an excellent coating material for the paper or paperboard. As illustrative of the general mixture used, a satisfactory coating composition has been made from a solution comprising approximately 50% to 60% of commercial latex containing approximately 40% rubber solids mixed with approximately 40% to 50% of liquid glue comprising approximately six pounds of water to one pound of fat-free glue solids. To this may be added a preservative, such as formaldehyde, and to retain the latex in a workable condition, standard ammonia may be added. The latex generally contains some ammonia and the amount to be added depends to a great extent on the speed at which coagulation of the latex is to be effected. Coagulation of the latex and the glue is effected by the application of alcohol to the latex glue solution, which is preferably applied during or immediately after the application of the latex glue mixture to the paper so as to prevent the possibility of any substantial coagulating action prior to the actual contact of the latex glue mixture to the paper surface.

I have found that a coagulating material which contains a major percentage of alcohol, and known commercially as Shellacol, has proven to be an excellent coagulating medium. To two gallons of the latex glue mixture comprising approximately 55% of latex having approximately 40% solid rubber content, and approximately 45% liquid glue is added approximately one-half ounce of formaldehyde, approximately 4 ounces of alcohol or Shellacol, and a sufficient amount of standard ammonia to keep the material workable

until the coating has been applied. It is understood that the proportions above given are illustrative only and the percentage of latex and liquid glue used may be varied within wide limits.

5 A coating composition comprising the latex liquid glue mixture to which a preservative has been added is preferably sprayed on to the surface of the paper or paperboard web as the web moves under the spray nozzles. The spray nozzles should be so arranged as to apply a uniform coating to the paper surface and to fully coat the same. The coated paper surface then immediately comes into contact with the spreader blade 10 which serves to even out any irregularities and give the finished material a smooth and even texture, filling in any uncoated areas of the paper surface. The spreader blade also assists in forcing the coating mixture into the surface so that a firm bond between the coating and the paper is produced. It has been found that the alcohol or coagulating agent may be added to the latex glue mixture at the nozzles where it is immediately ejected onto the paper surface with the latex glue mixture before it has an opportunity to coagulate the same. If the coagulating medium and the latex mixture are to be applied simultaneously the apparatus should be so constructed as to permit immediate ejection of both materials before any marked coagulating action can take effect.

30 The coagulating agent may also be separately applied by spray nozzles as the web leaves the spreader blade. The coated web is then run through a drying tunnel which may be suitably heated to expedite the escape of the fugitive components of the coating mixture, after which the paper or paperboard may be cut into sheets or wound upon the roll. It is also understood that 35 my process contemplates coating both sides of the paper or paperboard surface, if desired.

40 Under ordinary circumstances, it is known that latex and rubber compositions as generally manufactured deteriorate rapidly, and that in a few months' time the solidified latex loses a great deal of its elasticity and toughness. I have found, however, that when latex is combined with the alcohol and formaldehyde in the above proportions, that a preserving action is effected which 45 produces a coating which is strong, resilient, tough and durable, and is both waterproof and greaseproof. No deteriorating effects are noted many months after manufacture.

50 The apparatus for carrying out my improved process may comprise a spray apparatus A and a web-supporting, web-coating and web-drying machine B. The operating elements of the coating machine, as shown more particularly in Figs. 1, 2 and 3 of the drawings, may comprise a 55 supporting table including a horizontal frame 1 supported on the spaced legs 2, 3, 4 and 5. Suitable reinforcing struts 6 and 7 may be provided to stiffen and strengthen the table. Much of the operating apparatus is positioned at the head 60 end of the table and if preferable, therefore, the legs 2 and 3 may be relatively closely spaced to support the weight thereof.

65 A roll of the selected paper or paperboard P is supported by a shaft 10. The shaft 10 is rotatably mounted in suitable bearings 12 provided in each of a pair of brackets 11 supported by the table legs 2. The paper web P passes over a roller 13 having a resilient rubber surface. The roller 13 is fixed to a shaft 14 which is rotatably mounted in bearings 21 provided in the supporting

standards 15 standing on the table frame 1. The coating material is applied to the surface of the paper P as it passes over the roller 13. To maintain the paper web in a fixed plane as the coating mixture is applied, it is preferable to provide a guide roller 113 which is positioned between the paper roll P and the cylinder 13.

The coating material is preferably applied to the surface of the paper P under pressure of from 10 to 50 pounds per square inch. The apparatus for applying the coating solution is shown more particularly in Figs. 2 and 3 and may comprise generally a coating solution supply line 80 into which the coating solution is conducted through the conduit 81 from a suitable source of supply. The coating solution flows into the several branch conduits 82 each supplying a spray nozzle 83. Air pressure is used to expel the coating solution from the nozzles 83 in the form of a drenching mist, air under pressure from a suitable source of supply flowing into the air supply line 84. The air supply line 84 also has a plurality of branch conduits 85 extending therefrom, each branch conduit supplying its respective nozzle 83 with the desired air pressure which operates to expel the coating solution with the proper force. The nozzles 83 may be supported in stationary or adjustable position, as desired, upon the supporting bar 87, which is supported at each end by an upright 88 having a vertical telescoping adjustment with the associated supporting standard 89. The nozzles 83 are so spaced as to uniformly coat the paper surface with the required amount of coating material applied to the proper thickness and density.

Further means, including a spreader knife 22, is provided which operates to spread the coating solution onto the paper surface in a smooth uniform layer which will produce a coating sufficiently dense and uniform to fully protect the paper web P from contact with moisture or grease which may be applied to the coated surface. The spreader knife 22 comprises more particularly a heavy steel plate having the bottom surface 23 thereof shaped to accurately conform to the cylindrical surface of the roller 13. The spreader knife 22 is vertically adjustable in suitable guides provided on the standards 15. More particularly, vertical adjustment of the spreader knife 22 may be accomplished by means of suitable adjusting devices comprising a clamp element 24, fixed to each end of the spreader knife 22, each clamp 24 being secured in a suitable slide block 25 adapted to vertically slide within a guide opening 26 provided in each of the standards 15. An adjusting screw 28, provided with a hand wheel 29 to manipulate the same, extends through suitable threaded openings in the sliding block 25. By manipulating the hand wheels 29 at each end of the spreader knife 22, it is seen that the spreader knife may be raised and lowered as desired to present the lower spreading edge 23 thereof in the desired spaced position with respect to the paper web P passing over the roll 13. Thus the thickness of the coating applied to the web P may be regulated. The spreader knife 22 and associated guide block 25 may be removed from the standard 15 for repair or replacement by removing the guide plate 27 from its associated block 25, which guide plates retain the blocks 25 in fixed sliding position within the standards 15.

Preferably immediately following the spreading of the coating solution by means of the spreader knife 22, an additional solution which

will hereafter be called an accelerator, is preferably applied to the coated surface. The accelerator material contains constituents which will accelerate the hardening of the coating constituents and further assist in the escape of the fugitive components of the coating solution. The applicator for applying the accelerator solution may be similar to that used in applying the coating solution, comprising an accelerator solution supply conduit 80a which receives the solution from a suitable source and conducts it into the branch conduits 82a each of which supplies the accelerator solution nozzles 83a suitably supported upon a bar 87a extending horizontally across the moving web of coated paper P'. Air under pressure from a supply conduit 84a passes into the branch conduits 85a and acts to force out the accelerator solution through the nozzles 83a under pressure. A sufficient number of nozzles 83a are provided to apply the desired quantity of accelerator solution to the coated web. The nozzle-supporting bar 87a is in turn supported by suitable uprights 88a having vertical telescoping adjustment with the supporting standards 89. The accelerator solution, upon striking the coating solution, operates to congeal and harden the same and facilitate the escape of the fugitive or liquid components thereof.

It has been found that the accelerator solution under pressure may be supplied directly to the nozzles 83a which spray the coating material onto the web. The entry of the accelerator solution into the nozzles 83a should be so arranged so that the accelerator solution is not given an opportunity to congeal or harden the coating solution before it strikes the paper web.

As soon as the accelerator solution has been applied to the web, the web passes into a suitable drying tunnel 100 in which the coating applied to the web is hardened and dried. The drying tunnel 100 houses and encloses a considerable portion of the web-supporting table. A heated web-supporting roll 41 is fixed to a suitable shaft 42, the ends of the shaft being rotatably mounted in suitable bearings 43 carried by supporting brackets 44 resting on the table frame 1. The roll 41 is driven in synchronism with the roll 13 by operating mechanism which will hereinafter be described. The coated web P² in the process of drying is returned to the front end of the apparatus where it passes around a heated guide roll 45 fixed to a suitable shaft 46 rotatably mounted in bearings 47 suitably supported from the table frame 1. If desired, the guide roll 45 may be positioned outside of the tunnel housing 100 so as to permit inspection of the coating to determine the progress of the drying action. The coated web P² returns into the tunnel drier 100 and passes around a heated guide roller 50 at the foot end of the tunnel. The guide roller 50 may be supported on a suitable shaft 51 rotatably mounted in suitable bearings 52 supported by brackets 53 fixed to the supporting legs 5 of the table. If further drying action of the web P² is desired, the web may be again run through the drying tunnel to the front end thereof and passed around another heated guide roller 55 fixed to a suitable shaft 56 rotatably mounted in bearing 57 carried by suitable brackets 58 fixed to table-supporting legs 3. The web P² returns to the foot end of the tunnel and passes out of same through a suitable opening 66, at which point the coating on the web is dry and the coated web may be wound upon a suitable roll or cut into strips. It will be noted

that either one or both of the rolls 45 and 55 may be mounted inside or outside of the drying tunnel 100, as desired, and likewise the guide rolls 41 and 50 may be mounted either inside or outside of the drying tunnel 100. A suitable heating medium, such as steam, is conducted into each of the rolls 41, 45, 50 and 55 through a suitable supply conduit 42a connected to the hollow shaft which supports the rolls.

Suitable driving means are provided for driving the spreader roll 13 and the various guide rolls 41, 45, 50 and 55 in synchronism so that no undue stresses will be placed upon the web as it passes around these rolls. The driving force, such as a belt driven by a suitable motor, is trained around the stepped pulley wheel 18, which permits adjustment of the belt so that the apparatus can be run at any selected speed. Pulley wheel 18 is fixed to a suitable shaft 19 rotatably mounted in suitable bearings 20 supported by the table frame. A train of gears, comprising the gear 16 fixed to the shaft 19 which meshes with gear 17 fixed to one end of the shaft 14 of the roll 13, operatively connects the roll 13 with the drive pulley 18.

The various guide rolls 41, 45, 50 and 55 may be operatively connected to one end of the shaft 14 of the roll 13. More particularly, a bevel gear 31 fixed to one end of the shaft 14, meshes with a bevel gear 32 fixed to a longitudinally extending shaft 33 which operates to drive the guide roll 41 at the foot end of the apparatus. The shaft 33 may be rotatably mounted in suitable bearings 38 provided in the spaced brackets 34, 35, 36 and 37 fixed to the table frame 1. A bevel gear 39 at the foot end of the longitudinal shaft 33 meshes with bevel gear 44 fixed to the shaft 42 supporting the guide roll 41. The drive connection between the spreader roll 13 and the guide roll 41 is such that the peripheral speed of rotation of the guide roll 41 is the same as that of the spreader roll 13.

The guide roll 50 may be driven by means of a suitable drive connecting the shaft 42 of the roll 41 and the shaft 51 of the roll 50. This drive connection may comprise a sprocket gear 59 fixed to the shaft 42 of guide roll 41 over which is trained a drive chain 60 which is also trained over the sprocket wheel 61 fixed to the shaft 51 of the roll 50.

Guide roll 45 may be directly connected to the shaft 14 of the spreader roll 13 by means of suitable driving mechanism comprising a sprocket gear 62 connected to the shaft 14, a sprocket gear 64 attached to the shaft 46 of guide roll 45, the sprocket wheels 62 and 64 being connected by a suitable drive chain 63.

Likewise, guide roll 50 may be operatively connected to guide roll 45 by means of a sprocket wheel 65 attached to the shaft 46 of guide roll 45. A sprocket wheel 66 is attached to the shaft 56 of the guide roll 55 and finally a suitable drive chain 67 is operatively connected to the sprocket wheels 65 and 66.

The drive connection between the spreader roll 13 and the guide rolls 41 and 50, 45 and 55, is so arranged and adjusted that the peripheral speed of the spreader roll 13 and the various guide rolls is maintained substantially uniform, so as to obviate the possibility of any pulling stresses being exerted on the web passing around the same. It will be noted that separate drive means may be provided for one or all of the guide rolls 41, 50, 45 and 55, if desired, although it is generally

preferable to drive all the guide rolls as well as the spreader roll 13 from the same source of power so as to obviate the possibility of pulling stresses on the web which might otherwise develop.

Suitable drying means are preferably provided within the drying tunnel to hasten and facilitate the drying of the coated web. The drying means may comprise a suitable arrangement of steam or hot water heated coils, an electrical heating device, or other suitable heating means. I have shown and illustrated in Figs. 1 and 2 a heating device which comprises a plurality of parallel arranged pipes 70 suitably connected by elbows 71 to provide a continuous conduit of serpentine form. The inlet end 72 may be connected to a suitable steam or hot water supply. The cooled steam or water may be withdrawn from the outlet 73. The steam or hot water coils may be supported in suitable frames 74 suspended from the table frame 1. While only one row of heating coils is shown in Figs. 1 and 2 it is understood that two or more rows of heating coils may be provided positioned between adjacent moving webs. The coils are designed to maintain the temperature of the tunnel at from 180° to 350° F. A suitable outlet 101 is provided in the tunnel to permit the escape of the evaporable constituents of the coating. It is understood that the tunnel 100 may be of any length necessary to effect the desired drying action of the coating.

There is illustrated more or less diagrammatically in Fig. 5a somewhat modified apparatus adapted to coat both sides of the paper web P. In the arrangement here shown the paper or paper-board P to be coated is reeled off the roll supported on the shaft 10, which rotates in a suitable bearing 12 carried by a suitable supporting bracket 11a. The moving web P passes under the coating solution spray nozzles 83 which applies the coating to one surface of the paper web. The web then passes under the spreader knife 22 and thereafter passes under the accelerating solution spray nozzles 83a, and then into the drying tunnel 100 where it passes around the guide rolls 41, 45, 50 and 55 and 90. The apparatus so far described may be similar to the apparatus shown and illustrated in Figs. 1, 2 and 3 and heretofore described. When completely or partially dried the coated web P² passes out of the tunnel 100 through a suitable exit opening 105 and thereafter passes over a second spreader roll 13a which is similar in construction to the spreader roll 13 above described. It will be noted that the uncoated surface of the web P² is uppermost as it passes over the spreader roll 13a. A second coating solution spray nozzle 83 constructed similar to the spray nozzle heretofore described, applies the coating solution to the uncoated face of the web before it passes under the spreader knife 22a, as the web moves toward the left as shown in Fig. 5. The spreader knife 22a may be mounted and constructed similar to the spreader knife 22 heretofore described, and operates to spread the coating uniformly over the surface of the web. A series of accelerator solution spray nozzles 83a are positioned on the opposite side of the spreader knife 22a and operate to apply the solution to hasten the solidification of the coating solution. The web, coated on both sides, then passes around the rotatably mounted guide roll 106 and then passes through the inlet opening 106' in the tunnel drier 100 where the coating last applied is dried and finally hardened. The coated web P⁴ passes around the driven guide rolls 41a, 45a, 50a,

55a, and over the final guide roll 90a, at which point it passes out of tunnel drier 100 through the outlet opening 107 and is wound upon a suitable reel 108. The guide rolls 41, 45, 50, 55 and 90 and also the guide rolls 41a, 45a, 50a, 55a, and 90a may be operatively connected to and drive in synchronism with the spreader roll 13 in the manner heretofore described and may also be heated as above described. The apparatus herein described is adapted to coat both sides of the paper web and solidify the coating C so that the coating becomes homogeneously bonded to both surfaces of the paper web P, providing a coated paper P⁴ both sides of which is moisture and grease resistant.

In carrying out the process it is preferable to apply the coating solution immediately in advance of the spreader knife 22 so that the coating is not given the opportunity to solidify to any appreciable extent before it is acted upon by the spreader knife 22a. The accelerating solution applied by the spray nozzles 83a is preferably applied immediately following the passage of the coated paper web from under the spreader knife 22a so as to effect an initial congealing and hardening of the coating before it passes into the drying tunnel 100. While the above arrangement is preferable it is understood, however, that the accelerating solution may also be applied immediately prior to the passage of the coated web into contact with the spreader knife 22 and spreader knife 22a. The drying tunnel is of sufficient length to effect the case-hardening of the coating so as to remove any stickiness or tackiness therefrom as it passes around the guide rolls 45 and 55, where the coated surface of the paper web contacts these rolls. Where it would be inconvenient to provide a tunnel of sufficient length to effect this result it is understood that the coated web could be given a half twist so that the uncoated side of the paper web only would contact the front end guide rollers 45 and 55.

My improved method and apparatus is adapted not only for coating paper and paperboard material with any desired compound, such as that above described, but can also be advantageously used to coat other sheet materials, such as cloth, textiles and fabrics. It is, therefore, understood that where the words "paper" or "paper web" are mentioned in connection with the method and apparatus herein described and claimed, other webs of various sheet materials are also intended to be covered thereby. For example, waterproof and greaseproof cloth and textiles such as used in making raincoats, tarpaulin, oilcloth, linoleum, and like products, can also be manufactured by my improved method and apparatus herein described and claimed.

The invention embodied in this application is also directed to an improved waterproof and/or greaseproof paper and paperboard, which is well adapted for the manufacture of various commodities, such as paper bags, paper cement sacks, waterproof and/or grease proof wrapping papers, paperboard containers, cartons and boxes, for the shipment and storage of numerous products of commerce, either granular, liquid or semi-liquid in nature, and other products which require a waterproof and/or greaseproof container or wrapper.

While certain novel features of the invention have been disclosed and are pointed out in the annexed claims, it will be understood that various omissions, substitutions and changes may

be made by those skilled in the art without departing from the spirit of the invention.

What is claimed is:

1. The method of making coated sheet materials having waterproof and greaseproof characteristics which includes, providing a base sheet, preparing a coating compound by mixing latex, an aqueous solution of animal glue, a tanning agent and an alcohol, spraying a layer of the liquid or coating compound so formed onto one face of said base sheet, spreading said compound uniformly over said base sheet and simultaneously pressing the compound into the surface fibres of the base sheet to provide an impervious coating by wiping the coated face of the moving sheet into contact with a relatively rigid and stationary broad-edged element, and removing the liquid fugitive components from the body under treatment.
2. The method of making coated sheet materials having waterproof and greaseproof characteristics which includes, providing a base sheet, preparing a coating compound by mixing latex, an aqueous solution of animal glue, a tanning agent and an alcohol, projecting said coating compound over a surface of said base sheet, wiping the coated surface of the moving sheet into contact with a relatively rigid and stationary broad-edged element whereby to spread said compound uniformly over said base sheet and compress the compound into the surface fibres of the base sheet to provide an impervious coating, and removing the liquid fugitive components from the body under treatment.
3. The method of making coated sheet materials having waterproof and greaseproof characteristics which includes, providing a base sheet, preparing a coating compound by mixing latex, an aqueous solution of animal glue, a tanning agent and an alcohol, projecting said coating compound over the surface of said sheet as it moves along in a lineal direction, wiping the coated surface into contact with a relatively rigid and stationary broad-edged element whereby to spread said compound uniformly over said base sheet as it moves along in a lineal direction and simultaneously compress the compound into the surface fibres of the base sheet to provide an impervious coating, and removing the liquid fugitive components from the body under treatment.
4. The continuous method of making coated sheet materials having waterproof characteristics which includes, providing a continuous web of the base material, preparing a coating compound by mixing together from 40% to 60% of latex, 30% to 50% of liquid animal glue, a tanning agent, and an alcohol, applying said coating compound to the surface of said web during its lineal travel, wiping the coated surface of said moving web into contact with a relatively stationary broad-edged element whereby to spread said compound uniformly over and impress said compound into the surface fibres of said web during its lineal travel, and removing the liquid fugitive components from the body under treatment.
5. The continuous method of making coated sheet materials having waterproof characteristics which includes, providing a roll of continuous webbing of the base material, preparing a coating compound by mixing together from 40% to 60% of latex, 30% to 50% of liquid animal glue, a tanning agent, and an alcohol, projecting said coating compound over the surface of said

webbing during its lineal travel, wiping the coated surface into contact with a relatively rigid and stationary broad-edged element whereby to spread said compound uniformly over said webbing during its lineal travel and compress the compound into the surface fibres of the base

sheet to provide an impervious coating, removing the liquid fugitive components from the body under treatment, and placing said coated webbing in a roll.

HORACE A. SHEESLEY.
